Atty.

UNITED STATES PATENT OFFICE.

EMERY H. FAHRNEY, OF CHICAGO, ILLINOIS.

SNOWPLOW.

Application filed May 25, 1925. Serial No. 32,590.

This invention relates in general to snow plows of the type in which there is employed a rotary impeller for delivering the snow from the machine, but more specifically the 5 invention relates to improved means adapted for use in connection with the discharge chute of the impeller casing, the chute being provided with a discharge outlet leading through the end thereof and another discharge outlet leading through the side thereof, and one of the objects of the invention is to provide improved means for selectively controlling the outlet openings whereby the material delivered through the chute may be 10 selectively directed at will through one or the other of the said outlet openings, the said controlling means also operating as a deflector for the material.

To the attainment of these ends and the 20 accomplishment of other new and useful objects as will appear, the invention consists in the features of novelty in substantially the construction, combination and arrangement of the several parts hereinafter more 25 fully described and claimed and shown in the accompanying drawing illustrating this invention, and in which

Figure 1 is a front plan view of the scoop of a snow plow and impeller casing with 30 the discharge chute therefor, partly in section and having an attachment constructed in accordance with the principles of this invention applied thereto.

Figure 2 is a detail top plan view of the 35 outer end of the chute with the attachment applied thereto.

Referring more particularly to the drawing the numeral 10 designates generally the scoop of a snow plow having an opening 11 in the bottom thereof, through which the material is fed to an impeller 12, the latter being of any suitable construction and which 40 impeller discharges the material through a discharge chute 13, the latter being provided with a discharge outlet opening 14 through 45 the end thereof and a lateral discharge opening 15 through the side thereof.

The chute may be of any desired size and configuration, and is preferably provided 50 with guides 16 therein and on opposite sides thereof, and which guides arch in a direction across the chute and form a support for the ends of a plurality of elements 17 which are flexibly connected together, such as by 55 pivots, and which elements are adapted to

be projected across the chute to form a deflector for deflecting the material through the opening 15.

These elements 17 may be of any desired construction and are preferably connected at 60 their extremities with chain like devices 18, which latter are provided with rollers 19 adapted to engage and move upon the guides 16.

The chute 13 is preferably provided with 65 an opening 20 in the side thereof through which the elements 17 may be retracted or projected into the chute.

Any suitable means may be provided for shifting the deflector formed by the elements 70 17, such as toothed or sprocket wheels 21, which latter are connected with a shaft 22 journaled in suitable brackets 23 preferably secured to a support or to the chute 13. A pulley 24 may also be connected with the 75 shaft 22 and this pulley is adapted to be rotated from any suitable source.

With this improved construction it will be manifest that by controlling the adjustment or position of the deflector formed by 80 the elements 17 the direction of travel given to the material from the chute 13 by the impeller may be controlled. That is, the material may be caused to be delivered through the outlet 14 or the outlet 15 as desired. 85

When it is desired to deliver the material through the outlet 15 the deflector 17 is moved into the position shown in Figure 1. That is it is projected into and across the chute 13, thereby closing the outlet opening 90 14 to the discharge of material therethrough.

When the deflector 17 is retracted, it will be withdrawn from the chute and will stand adjacent the outside of the chute 13. When 95 in this position the material will be delivered through the outlet 14.

This construction is particularly advantageous in that when occasion may require, the snow or material being handled by the 100 impeller will be prevented from being delivered on the sidewalk or a portion of the road where it might be objectionable or in the way, and insures the delivery of the material at a position along the road bed or 105 line of travel of the machine.

While the preferred form of the invention has been herein shown and described it is to be understood that various changes may be made in the details of construction and 110

in the combination and arrangement of the several parts, within the scope of the claims, without departing from the spirit of this invention.

5. What is claimed as new is:—

1. In combination, a discharge chute having two outlet openings, one of said openings leading through the end of the chute and the other laterally through the side of the chute, a flexible deflector adapted to be projected across the chute for closing one of the said openings and for directing the material through the other of the openings, and means for causing the deflector to form 10 an arch across the chute intermediate the said opening.
2. In combination, a discharge chute having two outlet openings, one of said openings leading through the end of the chute and the other laterally through the side of the chute, a flexible deflector adapted to be projected across the chute for closing one 15 of the said openings and for directing the material through the other of the openings, and curved guides for guiding the said deflector in its movements whereby the deflector will be caused to arch across the chute.
3. In combination, a discharge chute, said chute having an outlet leading through the 20 end and an outlet leading through the side thereof, a flexible deflector adapted to be arched across the chute between the outlet openings for deflecting the material through the outlet in the side of the chute and for 25 closing the other outlet, and means exterior of the chute for actuating the said deflector at will.
4. In combination, a discharge chute, said

chute having an outlet leading through the end and an outlet leading through the side 40 thereof, a flexible deflector adapted to be projected across the chute between the outlet openings for deflecting the material through the outlet in the side of the chute and for closing the other outlet, means exterior of 45 the chute for actuating the said deflector at will, the said deflector embodying a plurality of elements pivotally connected together, and guides disposed adjacent the ends of the said elements.

5. In combination, a delivery chute having two outlet openings, a flexible deflector normally disposed outside of the chute, and means for projecting the deflector into and across the chute between the said openings to close one of the openings and for directing the material through the other of the said openings, the said deflector arching across the chute and embodying a plurality of elements swingingly connected together. 50

6. In combination, a delivery chute having two outlet openings, a flexible deflector normally disposed outside of the chute, means for projecting the deflector into and across the chute between the said openings to close one of the openings and for directing the material through the other of the said openings, the said deflector arching across the chute and embodying a plurality of elements swingingly connected together, 55 and guides within the chute for the ends of the said elements.

In testimony whereof, I have signed my name to this specification, on this 11th day of May, 1925.

EMERY H. FAHRNEY.
